UNITED STATES PATENT OFFICE.

WILLIAM J. SCHILLING, OF NEW YORK, N. Y.

DESIGN FOR MUCILAGE-HOLDERS.

Specification forming part of Design No. **11,254**, dated June 17, 1879; application filed May 22, 1879.
[Term of patent 7 years.]

To all whom it may concern:

Be it known that I, WILLIAM J. SCHILLING, of the city, county, and State of New York, have originated and designed a new form of Mucilage-Holders, of which the following is a full, clear, and exact description, reference being had to the accompanying fac-simile or drawing, which forms an essential part of this specification.

This invention relates to that class of vessels or bottles of peculiar shape and form intended for the reception of mucilage, such vessels being known to and designated in the trade as "fountain" or "reservoir" mucilage-stands.

The present design for such a bottle or vessel consists in an improved exterior configuration thereof.

Referring to the drawing, A represents the base of the stand, upon which are supported the reservoir or fountain B and the discharging mouth C.

The main wall or body B of the reservoir is concave in form, and is surmounted by a curved dome, D, a plain band, e, dividing such dome from the main body of the reservoir. The concave body B is preferably ornamented by means of a series of panels, a. The bases of such panels, where they unite with the base A of the vessel, are also ornamented by a raised figure, d, in the form of an inverted V. The curved dome D is also ornamented with a series of panels, b.

The mouth or well C is drawn closely to and projects directly from the body of the reservoir, as shown.

While I prefer the ornamentation of the reservoir as described, yet it may be left plain or ornamented by any other fanciful figures, my main object being to bring the reservoir and well closely together, and this is best obtained by the concave reservoir and form of well as shown.

What I claim as my invention is—

1. The design for a mucilage-stand, consisting of the fountain or reservoir B, the body of which is concave in form and surmounted by the curved dome D, such body and dome being divided by the band e and ornamented by the panels a b, such reservoir also being provided with a discharging mouth or well, C, projecting from one side and the base thereof, all substantially as herein shown and described.

2. The design for a mucilage-stand, consisting of the reservoir B, the body of which is concave in form and surmounted with a curved dome, D, and the discharging mouth or well C, projecting from one side of the reservoir B, both being mounted upon a common base, A, all substantially as herein shown and described.

WILLIAM J. SCHILLING.
